CROWN MELLOWER

Rudolph G. Segschneider, Yonkers, and Henri H. Kaufman, New York, N. Y.

Application September 1, 1944, Serial No. 552,305

7 Claims. (Cl. 223—7)

1

This invention relates to crown mellowers. It is particularly directed to a device for softening stiffness in crowns of hats.

In the hat making process, a stiffening solution such as shellac is applied to the hat so that the crown will maintain a desired shape during use. The present machine serves to break the stiffness around the headline or the bottom of the crown to make it easier to sew the sweatband and the outside band to the hat.

An object of this invention is to provide a device of the character described comprising rollers adapted to engage opposite sides of the crown of the hat and rotated so that the hat will rotate and the shellac or other stiffening material will be broken up and the crown mellowed or softened.

Another object of this invention is to provide a device of the character described comprising a table on which a hat is placed, a rotary roller on the table adapted to project into the crown, and a movable member holding rollers adapted to contact the outside of the crown to press the crown against the inner roller.

Yet another object of this invention is to provide a device of the character described in which the rollers on the outside of the crown are mounted on a lever which is acted on by a spring to press the rollers against the crown, and said device having means to retain the lever in a position where the rollers thereon are out of contact with the crown so that the crown may be removed.

Yet a further object of this invention is to provide a strong, rugged and durable crown mello-
lower of the character described which shall be inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a top plan view of a crown mello-
lower embodying the invention;

Fig. 2 is a partial elevational view taken on line 2—2 of Fig. 1 and with parts broken away and in cross-section;

Fig. 3 is a cross-sectional view taken on line 3—3 of Fig. 1;

Fig. 4 is a cross-sectional view taken on line 4—4 of Fig. 1; and

Fig. 5 is a cross-sectional view taken on line 5—5 of Fig. 1.

Referring now in detail to the drawing, 10 designates a crown mello-
lower or breaker embodying the invention. The same comprises a table 11 having a table top 12 supported on corner legs 13. The legs 13 may be reinforced by braces 14. The table 11 may have a top wall 15 formed with downwardly extending front and rear flanges 16 and 17 and side flanges 18.

Fixed to the underside of top wall 15 is a bracket 20. The bracket 20 may comprise a bracket member 21 having a top wall 22 fixed to the underside of wall 15, a vertical wall 23, and a horizontal wall 24 parallel to wall 22. Fixed within bracket member 21 is an inner bracket member 25. Bracket member 25 comprises a vertical wall 26 parallel to wall 23, a horizontal arm 27 at its upper end contacting and fixed to the underside of wall or arm 22, and an arm 28 at the lower end of wall 26 contacting and fixed to arm or wall 24. Arms 27 and 28 are formed with vertically aligned half bearings 29 and 30 to which are attached complementary half bearings 29a and 30a. Top wall 15 is formed with a vertical through opening 32 vertically aligned with the bearings 29, 29a, and 30, 30a. Arms 22 and 24 are furthermore formed with openings 33 aligned with said bearings and with the opening 32.

Extending through said bearings and through the openings 32 and 33 is a vertical shaft 34 projecting above the table top 15. Fixed to the upper end of shaft 34 is a knurled roller 36 disposed just above table top 12. Shaft 34 projects below bracket 20 and fixed to the lower end thereof is a pulley wheel 38.

The front legs of the table 11 are provided with a pair of parallel cross braces 40. Mounted thereon is an electric motor 41 having a vertical armature shaft 42. On said shaft is a pulley 43 aligned with pulley 38 and interconnected therewith by a belt 44. When motor 41 is energized, shaft 34 and hence roller 36 will be rotated.

The table top 12 is formed at one side thereof with a boss 47. Screwed to the boss is a pin 48 forming a pivot. Pivoted on said pivot is a horizontal lever arm 50 overlying the table and extending therebeyond. Attached to one end of the arm 50 is an upwardly extending handle 51. Attached to the underside of arm 50 is a plate

52. Fixed to said plate are a pair of spaced vertical pins 53. Rotatably mounted on the pins 53 are spaced rollers 54. The rollers 54 are so located that when arm 50 is rotated in a clockwise direction toward roller 36, the latter will fit between and contact the rollers 54.

In the drawing H designates a hat such as a felt hat or a straw hat placed on the table with the brim 55 of the hat on the table and the crown 56 disposed between the rollers 36 and 54. When the motor is started and lever 50 is moved toward the hat, rotation of the roller 36 will cause the hat to rotate, thereby causing rotation of the rollers 54 and during this process the crown will be mellowed, that is the shellac, gum starch or other stiffener at the base of the crown will be broken up and the crown softened. Rollers 54 will press the crown against roller 36 to cause the hat to rotate.

Spring means is provided to press the rollers 54 toward the roller 36. To this end there is fixed to one of the flanges 18 of the table top 12, an anchor pin 60. On lever 50 is a pin 61 disposed just beyond one side of the table. Interconnecting the pins 60 and 61 is a coil compression spring 62. It will now be understood that the spring 62 presses the rollers 54 toward roller 36 so that the crown is gripped between the rollers.

Means is provided to hold the rollers 54 away from roller 36 when the mellower is not in use. To this end there is fixed on top of the table 12, and adjacent one side thereof, a bracket 70. Bracket 70 comprises a Z-shaped member 71 having an arm 72 contacting the top of the table and fixed thereto by screws or other fastening means 73. Member 71 also has an arm 74 disposed parallel to and spaced above the table top 12. Fixed to the top of arm 74 is a stop plate 75 terminating short of the rear end of arm 74. The pivoted arm 50 is adapted to contact the rear edge 76 of stop plate 75 and thereby being held in hat releasing position as shown in Fig. 1 of the drawing. In order to move the rollers 54 toward the hat, handle 51 is somewhat raised to disengage the pivot arm from the edge 76 of plate 75. Then the spring 62 is allowed to swing the pivoted arm in a clockwise direction so that the rollers engage the crown and rotate the hat.

Arm 74 is formed with a hole. Attached to plate 75 is a pin 75a projecting down through said hole in arm 74. At the lower end of the pin is a head. Interposed between the head and the underside of arm 74 is a spring 75b. The spring 75b permits some flexing of arm 74 relative to plate 75.

Means is provided to keep the crown 56 of the hat H upright and to guide the hat as the hat is rotated. To this end there is fixed to the table top a pair of spaced headed screws 80. Screws 80 serve to clamp a guide member 81 to the table top. Member 81 may be made of heavy wire stock and has a pair of parallel arms 82 disposed on opposite sides of the screws 80 and held down by means of washers 83 pressed by the heads of the screws against said arms. Extending from arms 82 are upwardly inclined arms 85 interconnected by a vertical loop portion 87. The portion 87 contacts the inside of the crown at a point spaced from the portion engaged by the rollers. Said portion 87 is so located as to position the hat substantially on the table as it rotates under the influence of the rollers.

It will thus be seen that there is provided a device in which the several objects of this inven-

tion are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. A crown mellower comprising a stationary support for a hat, a roller on said support adapted to contact the inside of the crown of the hat adjacent its base, means to rotate the roller, a member movably mounted on said support, and a roller on said member, said second roller being movable toward the first-mentioned roller into engagement with the outside of the crown of the hat adjacent its base whereby to cause said hat to turn on said support.

2. A crown mellower comprising a stationary support for a hat placed thereon, a roller on the support adapted to engage the inner side of the base of the crown of the hat placed on said support, a roller adapted to contact the outer side of the crown of the hat, and press the crown against the inner roller, means to rotate one of said rollers to cause the hat to turn and the other of said rollers to rotate as the hat turns, means to move one of the rollers away from and toward the other roller, and resilient means to press the rollers toward each other.

3. A crown mellower comprising a support for a hat placed thereon, a roller on the support adapted to engage the inner side of the base of the crown of the hat placed on said support, a roller adapted to contact the outer side of the crown of the hat, and press the crown against the inner roller, means to rotate one of said rollers, means to move one of the rollers away from and toward the other roller, resilient means to press the rollers toward each other, and means to maintain the rollers in separated condition.

4. A crown mellower comprising a table having a table top, a vertical shaft rotatably mounted on said table, and extending through the table top, a roller at the upper end of said vertical shaft, and means on the table to rotate said shaft, a lever arm pivoted to the table and movable in a plane parallel to the table top and extending beyond one side of the table top, a handle on said lever arm, a bracket fixed to the lever arm, and a pair of rollers on said bracket, and adapted to be moved into contact with the first-mentioned roller.

5. A crown mellower comprising a table having a table top, a vertical shaft rotatably mounted on said table, and extending through the table top, a roller at the upper end of said vertical shaft, and means on the table to rotate said shaft, a lever arm pivoted to the table and movable in a plane parallel to the table top and extending beyond one side of the table top, a handle on said lever arm, a bracket fixed to the lever arm, a pair of rollers on said bracket, and adapted to be moved into contact with the first-mentioned roller, and a spring interconnecting the lever arm and the table.

6. A crown mellower comprising a table having a table top, a vertical shaft rotatably mounted on said table, and extending through the table top, a roller at the upper end of said vertical shaft, and means on the table to rotate said shaft, a lever arm pivoted to the table and mov-

able in a plane parallel to the table top and extending beyond one side of the table top, a handle on said lever arm, a bracket fixed to the lever arm, a pair of rollers on said bracket, and adapted to be moved into contact with the first-mentioned roller, a spring interconnecting the lever arm and the table, and a bracket fixed to the table top and adapted to engage the lever arm to maintain the pair of rollers away from the first-mentioned roller.

7. A crown mellower comprising a support for a hat placed thereon, a roller on the support adapted to engage the inner side of the base of the crown of the hat placed on said support, a roller adapted to contact the outer side of the crown of the hat, and press the crown against the inner roller, means to rotate one of said

rollers, and fixed guide means on said support adapted to engage the inside of the crown of the hat above the base.
